HYSTERESIS CONTROL FOR A SCHMITT
TRIGGER CIRCUIT

Thomas Weisz, Ossining, N.Y., assignor, by mesne assignments, to U.S. Philips Corporation, New York, N.Y., a corporation of Delaware

Filed Mar. 24, 1966, Ser. No. 537,071

9 Claims

This invention relates to trigger circuits, and more in particular to improved Schmitt trigger circuits in which control of hysteresis may be achieved without substantial deterioration of the frequency characteristics of the circuit.

It is well known that hysteresis can be reduced in Schmitt trigger circuits by suitable selection of the circuit components, and that a condition of zero hysteresis can be achieved when the loop gain of such a circuit is unity. The conventional approach to the reduction of hysteresis, however, generally results in a reduction in the switching speed and cycle speed of the circuit.

It is therefore an object of this invention to provide a Schmitt trigger circuit having means for reducing the effects of hysteresis without greatly affecting the frequency characteristics of the circuit.

A further object of the invention is to provide an economical and simple means for controlling the hysteresis effect in a Schmitt trigger circuit, whereby the switching speed of the circuit is not substantially reduced, and the stability of the circuit is not substantially affected.

According to the invention, a Schmitt trigger circuit is provided including switch means responsive to the conductive state of one of the amplifier devices in the trigger circuit for controlling the response of the circuit to input voltages. The switch means may, for example, control the voltage across the common feedback resistor as a function of the conductive state of the output amplifier device. By thus providing the hysteresis control means externally of trigger circuit loop, the trigger circuit may be designed to have the optimum switching speed characteristics without the necessity of compromising these characteristics for the sake of reduced hysteresis.

While the specification concludes with claims particularly pointing out and distinctly claiming the subject matter which I regard as my invention, it is believed that the invention will be better understood from the following description taken in connection with the accompanying drawings, in which: FIG. 1 is a circuit diagram of one basic form of a known Schmitt trigger circuit; FIG. 2 is a circuit diagram of a known modification of the circuit of FIG. 1 for reducing the effects of hysteresis; FIG. 3 is a circuit diagram of one embodiment of a Schmitt trigger circuit according to the invention, including means for controlling the hysteresis of the circuit;

FIG. 4 is a circuit diagram of a modification of the circuit of FIG. 3, and FIG. 5 is a circuit diagram of another embodiment of a Schmitt trigger circuit according to the invention.

Referring now to the drawings, FIG. 1 illustrates one form of a basic Schmitt trigger circuit. In this circuit, an input terminal 10 is connected to the base of a transistor Q₁, and the collector of transistor Q₁ is directly connected to the base of transistor Q₂. The collector resistor R₁ of transistor Q₁, and the collector resistor R₂ of transistor Q₂ are connected to one terminal V_{cc} of a source of operating potential, and a common emitter resistor R₃ is connected to ground. An output signal may be obtained from a terminal 11 connected to the collector of transistor Q₂.

In this circuit, when the voltage applied to the input terminal is below a predetermined value V₁, the transistor Q₂ will conduct and produce a voltage drop V₂ across

2

the common emitter resistor R₃. Assuming that transistor Q₂ is saturated so that the voltage drops in this transistor may be neglected, the resistors R₁ and R₂ are effectively in parallel, so the voltage drop across R₃ is dependent in part upon the resistance of R₁. If the input voltage now increases to V₁=V₂+v, wherein v is the base-emitter threshold voltage of transistor Q₁, the transistor Q₁ will start to conduct. If the positive feedback by way of resistor R₃ is sufficiently high, transistor Q₁ will be driven to saturation and transistor Q₂ will be cut off at a high switching speed. The resistor R₃ will now be in series effectively only with resistor R₁, when the input voltage approaches the threshold level, to produce a voltage drop V₃ across resistor R₃ which is lower than the voltage V₂. In order to cut off transistor Q₁, the input voltage must thus drop to a lower voltage than V₁, so that the threshold voltage, for changing the conduction conditions in the circuit are dependent upon the direction in which the input voltage changes. This effect is known as hysteresis.

The hysteresis effect can be reduced, as shown in FIG. 2, by including a resistor R₄ in series with the base lead of Q₂ and making resistor R₁ equal resistor R₂, so that the voltage V₂ is less dependent upon the base circuit resistance of transistor Q₂. The resistor R₄, however, lowers the circuit gain so that the switching time of the circuit in response to an input voltage change is increased. The increase in switching time may be overcome by the use of a capacitor C₁ in parallel with the resistor R₄, but this capacitor introduces a time constant in the circuit that reduces the cycle time, i.e. the minimum time that the circuit can pass through both conduction states and be prepared to respond to a new change of the input voltage. Thus, while the circuit of FIG. 2 reduces the hysteresis effect, the additional components required introduce time delays. In addition, in the circuit of FIG. 2, the hysteresis is a function of the characteristics of the transistors, which may vary on the time (aging) and temperature. This circuit is also unstable for D.C. input voltages as a result of the finite base-emitter resistance of transistor Q₁. (This problem is not present in the circuit of FIG. 1 since resistor R₁ can be made large enough to ensure cutting off of transistor Q₂, thus providing stable operation.)

Referring now to FIG. 3, according to one embodiment of the present invention, the circuit of FIG. 1 is modified by providing a transistor Q₃. The collector of transistor Q₂ is connected to the base of transistor Q₃ by series connected R₅ and R₆. A bias source V_b is connected between the emitter of transistor Q₃ and the emitters of transistors Q₁ and Q₂. A capacitor C₂ is connected between the junction of resistors R₅ and R₆ and the emitters of transistors Q₁ and Q₂. The collector resistor R₇ of the transistor Q₃ is variable and is connected to V_{cc}.

In this circuit, when the input voltage is sufficiently low that transistor Q₂ is saturated, the emitter collector voltage of transistor Q₂ is lower than the sum of V_b and the base-emitter threshold voltage of transistor Q₃, so transistor Q₃ is cut off. When the input voltage is increased to V₁ and transistor starts conducting, the conduction conditions of transistors will change as in the circuit of FIG. 1. Resistors R₅ and R₆, the capacitor C₂, and the input capacitance of transistor Q₃ form a time delay network with a time delay sufficiently long that transistor Q₃ does not start to conduct until the switching of transistors Q₁ and Q₂ has been completed.

The circuit of transistor Q₃ thus does not interfere with the switching of transistors Q₁ and Q₂ when the input voltage is increasing and the switching speed of the original Schmitt trigger circuit is preserved. Similarly, when transistors Q₁ and Q₃ are conducting and transistors Q₂ is nonconductive, a transition of conducting states of the transistors Q₁ and Q₂ resulting from a decrease of the input voltage will not be affected by the presence of transistor

Q_3 since the time delay network will hold the transistor Q_3 in its conductive state until the switching has been completed.

When the transistor Q_3 becomes conductive, its emitter current flows in common emitter resistor R_3 , and this current can be controlled by varying the resistance of collector resistor R_7 . By varying the value of resistor R_1 , the voltage drop across R_3 when transistors Q_1 and Q_3 are conducting can be made the same as the voltage drop V_2 when only the transistor Q_2 is conducting. The hysteresis of the circuit may be thus made equal to zero, or if desired, it can be made negative (with a sufficiently high rate of rise of the input voltage) or positive, by a single adjustment. Since the transistor Q_3 is not conductive during the transition period of switching of transistors Q_1 and Q_2 , the circuit of transistors Q_1 and Q_2 can be designed to provide a maximum switching speed. By design of the time delay network so that the transistor Q_3 becomes conductive (or non-conductive) as soon as possible after the switching of transistors Q_1 and Q_2 , and the cycle time of the circuit is not substantially increased. The control of hysteresis in this circuit is almost immune to transistor characteristics.

In the modification of the circuit of FIG. 3 shown in FIG. 4, the resistor R_6 has been omitted since the base resistance of transistor Q_3 can serve the same function. The source V_b has been replaced by a diode D_1 poled in the same direction as the base-emitter rectifier of transistor Q_3 to provide a sufficient threshold level that transistor Q_3 will not conduct when transistor Q_2 is saturated. Similarly, a diode D_2 has been inserted between the collector of Q_1 and the base of Q_2 to provide a sufficient threshold level that transistor Q_2 will not conduct when transistor Q_1 is saturated. The base of transistor Q_2 is connected to the bottom of resistor R_3 by means of resistor R_2 . The input circuit comprises a voltage divider of resistor R_9 , potentiometer R_{10} , and resistor R_{11} , with the input terminal being connected by way of capacitor C_3 to the junction of resistor R_{11} and potentiometer R_{10} . The arm of potentiometer R_{10} is connected to the base of transistor Q_1 to permit adjustment of the triggering level. A circuit according to FIG. 4 was constructed using the following components: R_1 —22K ohms; R_2 —2.2K ohms; R_3 —47 ohms; R_5 —100K ohms; R_7 —2.5K ohms; R_8 —22K ohms; R_9 —1.2K ohms; R_{10} —200 ohms; R_{11} —47 ohms; C_2 —500 pf.; C_3 —1 mf.; Q_1 —2N1304; Q_2 —2N1304; Q_3 —2N1305; D_1 —1N617; D_2 —1N457; V_{cc} —6 volt source. This circuit was employed successfully as a detector for half sine wave signals of 200 nanosecond duration and 10 millivolt magnitude at a repetition rate of 2 megacycles. The rise and fall times of the output voltage were 20 nanoseconds.

In a variation of the circuit of FIG. 4, as shown in FIG. 5, the current in the resistor R_3 is adjusted by means of an additional trigger circuit. The collector of transistor Q_2 in this case is connected to the base of a transistor Q_4 connected as an inverter amplifier. The collector resistor R_{15} is connected to V_{cc} and the emitter resistor R_{16} of the inverter is connected to ground. The inverted output at the collector of transistor Q_4 is connected to the base of a transistor Q_5 , and the collector of transistor Q_5 is connected to the base of transistor Q_6 . The collector resistors R_{17} and R_{12} of transistors Q_5 and Q_6 respectively are connected to the source V_{cc} . The emitters and transistors Q_5 and Q_6 are connected to the emitter resistor R_3 .

The transistors Q_5 and Q_6 comprise a second Schmitt trigger circuit coupled by the inverter Q_4 so that transistors Q_2 and Q_5 conduct at the same time, and transistors Q_1 and Q_6 conduct at the same time. The voltage drop across common emitter resistor R_3 can be varied by varying the collector resistor R_{18} of transistor Q_6 in order to obtain any desired hysteresis effect. In this circuit, the inverter transistor Q_4 is also to act as a circuit delay so that the second Schmitt trigger does not interfere with the switching action of transistors Q_1 and Q_2 . The trans-

sistor Q_4 is operated in saturation, and is selected to have a storage time greater than the switching time of the circuit of transistors Q_1 and Q_2 . The circuit provides the advantage of a less critical delay circuit, but the cycle time is increased since it must now include the switching time of the second trigger circuit. In a practical embodiment of the circuit of FIG. 5, operating in the non-saturating mode, sinusoidal input signals of 15 megacycles were successfully detected with a resolution of one millivolt.

While the invention has been described with reference to specific examples, it is obvious that many modifications may be made without departing from the spirit or scope of the invention. Thus, for example, the invention may be employed in vacuum tube circuits. Similarly, additional components may be employed in the circuit according to the invention in order to prevent saturation of the transistors, according to conventional practices, without departing from the teaching of the invention, and it is intended in the appended claims to cover all such changes as fall within the true spirit and scope of the invention.

I claim:

1. A trigger circuit comprising means for defining a bistable trigger circuit including cascaded alternately switched first and second amplifying means each having a common electrode coupled together, a common impedance coupled to said common electrodes, and means for compensating hysteresis effects in said trigger circuit comprising a time delay means having a time delay greater than the switching speed of said first and second amplifying means and having an output and having an input coupled to said second amplifying means, and means for increasing the current flow in said common impedance when said first amplifying means is conducting comprising third amplifying means coupled to the output of said delay means and having a common electrode coupled to the beforesaid common electrodes.
2. A circuit as claimed in claim 1 wherein said amplifying means and said common electrodes comprise transistors having emitters respectively.
3. A circuit as claimed in claim 1 wherein said delay means comprises a series resistor shunt capacitor network.
4. A circuit as claimed in claim 1 wherein said common impedance comprises a resistor.
5. A circuit as claimed in claim 1 further comprising means for biasing coupled in series with the common electrode of said third amplifying means.
6. A circuit as claimed in claim 1 further comprising means for adjusting the amount of hysteresis compensation.
7. A circuit as claimed in claim 1 wherein said time delay means comprises an inverter amplifier and said third amplifying means comprises cascaded alternately switched fourth and fifth amplifying means each having a common electrode coupled to the beforesaid common electrodes.
8. A circuit as claimed in claim 7 wherein said amplifying means and said common electrodes comprise transistors having emitters respectively.
9. A circuit as claimed in claim 7 further comprising means for adjusting the amount of hysteresis compensation.
